US0D1086234S

(12) **United States Design Patent** (10) Patent No.: **US D1,086,234 S**
(45) Date of Patent: ** Jul. 29, 2025

(54) **REFRIGERATOR**

(71) Applicant: **LG Electronics Inc.**, Seoul (KR)

(72) Inventors: **Myungshik Kim**, Seoul (KR);
Kyukwan Choi, Seoul (KR); **Joosang Kim**, Seoul (KR); **Minsub Kim**, Seoul (KR); **Sungkyong Han**, Seoul (KR); **Yong Kim**, Seoul (KR); **Yezo Yun**, Seoul (KR)

(73) Assignee: **LG ELECTRONICS INC.**, Seoul (KR)

(**) Term: **15 Years**

(21) Appl. No.: **35/521,253**

(22) Filed: **Jun. 9, 2023**

(80) **Hague Agreement Data**

Int. Filing Date: **Jun. 9, 2023**

Int. Reg. No.: **DM/231609**

Int. Reg. Date: **Jun. 9, 2023**

Int. Reg. Pub. Date: **Jun. 14, 2024**

(30) **Foreign Application Priority Data**

Dec. 9, 2022 (KR) 30-2022-0051911

(51) **LOC (15) Cl.** **15-07**

(52) **U.S. Cl.**

USPC **D15/86**

(57) **CLAIM**

The ornamental design for a refrigerator as shown and described.

DESCRIPTION

1. Refrigerator

1.1 : Top perspective view

1.2 : Bottom perspective view

1.3 : Front

1.4 : Back

1.5 : Left

1.6 : Right

1.7 : Top

1.8 : Bottom

(Continued)

The broken lines depict portions of the refrigerator that form no part of the claimed design; the design has pocket handles at the top and bottom doors to simplify the overall and facilitate user movement.

1 Claim, 8 Drawing Sheets
